UNITED STATES PATENT OFFICE

JOHN L. MANDEVILLE, OF ARLINGTON, NEW JERSEY, ASSIGNOR TO OXWELD
ACETYLENE COMPANY, A CORPORATION OF WEST VIRGINIA

ACETYLENE GENERATOR

Application filed September 3, 1925. Serial No. 54,322.

This invention relates to acetylene generators, and more particularly to portable acetylene generators in which calcium carbide is fed automatically into water in the generator when the supply of gas therein falls below a predetermined volume or pressure.

One of the principal objects of this invention is to provide an improved acetylene generator in which the feed of the carbide is automatically controlled by mechanism that is quickly responsive to variations of the gas pressure in the generating chamber.

The further object of this invention is to provide an apparatus for the generation of acetylene having a simple unitary construction, especially adapted for portable service, in which one compartment contains the gas generating means, and an adjoining compartment contains the feed control buoyancy member as well as auxiliaries, such as a filter, a pressure regulating valve and a back pressure valve.

Another object of this invention is to provide an acetylene generator that is capable of operating satisfactorily and automatically under heavy overloads, and strong enough to withstand the severe conditions to which it is subjected in field service.

The above and other objects and advantages of the invention will become apparent from the following description taken with the accompanying drawings, in which:

Fig. 1 is a perspective view of an embodiment of the present invention, with parts broken away to expose the interior construction;

Fig. 2 is an enlarged sectional view of the upper part of the acetylene generator shown in Fig. 1 with parts omitted for clarity to show the calcium carbide hopper with the feed control mechanism associated therewith; and

Fig. 3 is a vertical sectional view of the improved generator, parts being broken away, to show the side of the partition that is hidden in Fig. 1.

Generally speaking, the improved generator comprises a sheet metal tank T adapted to contain water and having its interior divided to provide a generating chamber G and

a buoyancy chamber F. These chambers may be formed, as shown, by a diametrical partition P extending from the top of the tank to a short distance above its bottom, whereby the chambers communicate with one another and any variation of gas pressure in the generating chamber is directly transmitted through the water therein to the buoyancy chamber to cause the operation of the carbide feed control mechanism. This improved mechanism comprises a heavier-than-water buoyancy in the form of a feed pan A which, as shown, may consist of a substantially rectangular open top vessel that is adapted to be filled with water and is suspended by suitable means, as by chains 10 and a rod 11, from the free end of a feed lever L pivoted at its fixed end on a bracket 12 and operatively coupled intermediate its ends to a carbide feed valve V that controls the carbide outlet 13 of a carbide hopper H in the upper end of the generating chamber G. Auxiliary devices, such as a filter B, a pressure regulating valve C, a hydraulic back-pressure valve D, and piping may be mounted within the buoyancy chamber and in the generating chamber, thus eliminating these as obstructions on the outside of the tank.

The generating chamber G is gas tight, being sealed by water in the bottom thereof and closed at the top by a plate 15 and the carbide hopper that is secured in an opening in said plate. As shown, the carbide hopper may have a tapering lower end provided with the discharge outlet 13 that is controlled by a suitable feed valve V, which may be of the conical receding type. A spring pressed shut-off valve V' may also be provided. The valves V and V' may be carried by a valve rod 16 that projects upwardly through a housing 17 secured centrally in the hopper, as by suitable brackets 18 and a carbide support and deflector 19. A helical spring S in the housing 17 tends to close the valve V. The lower end of said spring bears against an abutment 171 secured to the housing 17 and the upper end thereof bears against a sleeve 20 that is slideable through the stationary housing cap 172 and engages a nut 21 or other shoulder adjacent the upper end of the rod 16, thus tend-

ing to raise the latter and the valve V thereon to close the outlet 13.

When the generator is operating, the movement of the carbide valve V is controlled by the feed lever L which, in turn, is controlled by the feed pan A that descends and rises in accordance with pressure variations in the generating chamber. As acetylene is withdrawn from the generating chamber, the 10 water in the latter rises to displace the gas drawn off. This causes the water in the buoyancy chamber to descend and permits the weight of the water in the feed pan A to operate through the lever L and connections 15 against the carbide valve spring S and gas pressure against the diaphragm 28 to open the carbide valve V. As the carbide falls into the water in the generating chamber, the acetylene produced by the carbide-water re- 20 action displaces water in the generating chamber and causes the water level in the buoyancy chamber to rise and buoy the feed pan A and so permit the valve spring S to close the valve V.

25 The operative connection between the lever L and the spring S may comprise a pin 22 that is pivoted at 23 intermediate the ends of the lever L and has its free end bearing in a socket 24 at the outer end of a plunger 25 that is 30 slidable in a central hole 26 in the carbide charging door 27. The inner end of the plunger 25 extends through and is secured to a diaphragm 28 by a bolt 29. The diaphragm 28 prevents gas and air leakage past the 35 plunger 25, and the bolt 29 constitutes a head that thrusts against but is not mechanically connected to nut 30 or head on the upper end of the valve rod 16. Accordingly, when the plunger 25 is depressed by the lever L and 40 pin 22, the nut 29 thrusts against and depresses the nut 30 and the rod 16 carrying the latter to open the valve V. In one extreme position, the diaphragm 28 seats in a depression 31 in the inner side of the charging door 27, and its movement in the opposite direction is limited by a concave guard 32, both the diaphragm and guard being secured to the inner side of the charging door. The charging door may be held in gas tight relation to 45 an opening 33 of the hopper cover plate 34 by a swingable clamp bar 35 hinged at 36 and fastened by the swing bolt and wing nut 37 fitting into the forked end of bar 35. The arrangement of the carbide feed control 50 means is such that the parts may be quickly and easily disconnected and reconnected when the door 27 is to be opened and closed to charge carbide into the hopper H. The upper end of the rod 11 may be withdrawn from 55 the forked free end of the lever L, whereupon the latter may be swung about its pivot 121 on the bracket 12 into a position to hang along the outside of the tank, the outer end of the bracket overhanging the side of the tank suffi- 60 ciently for this purpose. Since the pin 22

merely rests in the socket 24, no mechanical manipulation is needed at that point, except raising the lever L. An opening 351 in the clamp 35 is of sufficient size to swing clear of the upper end of the plunger 25. The piston 25, diaphragm 28 and guard 32 are carried with the charging door when the latter is lifted off its seat, the guard 32 being provided with a central opening 321 of sufficient size to clear the nuts 21 and 30 at the upper end of the valve rod 16. Replacement of the charging door is substantially the reverse of and as simple as its removal.

The feed pan A is filled with water to provide a heavier-than-water buoyancy member which is supported partly by the buoyancy of the water in the float chamber and partly by the valve spring S and gas pressure against the diaphragm 28, suitable pan guides 136 being secured to the partition P to prevent any possibility of wedging or catching of the pan. This arrangement affords a very sensitive control for the carbide feed valve V, so that the latter is quickly responsive to changes in gas pressure in the generating chamber and a comparatively constant acetylene pressure is maintained in the generating chamber under severe service conditions as well as under normal operating conditions. The improved generator 95 is therefore especially adapted for blowpipe work where constancy of pressure is a necessity.

The chambers are desirably semi-circular in cross-section, as shown, but they may be circular and concentrically arranged one within the other, or of other suitable section. The two chambers are preferably of about the same cross-sectional area, so that any variation in pressure or volume in the generating chamber will be transmitted directly in practically equal amount to the feed pan A which controls the carbide feed. By this construction, the range of movement of the feed pan is kept within practical limits, 105 which would not be the case if the area of the buoyancy chamber were very small compared with the generating chamber; and on the other hand, if the area of the latter were decidedly smaller than that of the former, the 110 movements of the feed pan would be insufficient for practical purposes.

The acetylene generated by the interaction of calcium carbide and water collects in the upper part of the generating chamber. 115 The gas passes downwardly through a stand-pipe 137 having a water sealed pipe 38 at the lower end thereof to drain off any condensation, and into a tee connector 39 which passes through the partition P and is joined by suitable means to the inlet 40 of a suitable filter B, which is desirably located in the buoyancy chamber above the feed pan. The outlet of the filter is connected with the inlet of a pressure regulator C that controls the gas pres- 120

sure in the system. Any dependable type of regulator may be used, but a positive pressure non-adjustable type set at approximately one-half pound is preferred. The supply 5 of gas passes from the regulator through a control cock 41 to a hydraulic back pressure valve D having a service fitting 42 connected thereto, which is readily insertable into the end of a hose leading to a blowpipe or the like. Water may be filled into the back-pressure valve D by means of a filling fitting 43 and water level fitting 43' or drained therefrom by a drain fitting 44. Fittings 43', 44 and the service fitting project through 10 the side of the tank as may be clearly seen from Fig. 1. The piping and auxiliaries are supported by the partition and the wall of the tank, the auxiliaries being located within the buoyancy chamber so that the 15 tank is free from large exterior obstructions, except for a pair of carrying handles 45 and a residuum gate 46. Of course, the auxiliaries may be hung on the outside of the generator without affecting their operation 20 or that of the generator. The top of the buoyancy chamber is open to the atmosphere but may be provided with a pair of hinged perforated covers 47 lying on opposite sides of the rod 11.

30 The generator may be provided with an agitator comprising a staff 48 disposed vertically in the float chamber, having a handle 49 adjacent the top of the tank, and a sweep arm 50 near the bottom and projecting under 35 the lower edge of the partition into the generating chamber. The agitator is carried by a mounting 51 which is secured to the bottom of the tank. The agitator may be oscillated back and forth by the handle 49 to stir 40 any sediment in the bottoms of the chambers that may have formed from the lime produced by the carbide-water reaction, and to facilitate the removal of the sludge from the tank. A suitable baffle 52 having side wings 45 52' may be provided to prevent carbide from drifting into the buoyancy chamber. A baffle 53 is adapted to keep sludge from moving over to the float chamber, and baffle 54 is adapted to deflect gas and prevent it from 50 rising into the float chamber. The baffles 52 and 54 may be secured to opposite sides of the partition. A suitable water overflow outlet 55 may also be provided.

55 The operation of the generator is practically self-evident from the foregoing description. In order to fill the carbide hopper with calcium carbide, the feed pan rod 11 is unhooked from its socket at the end of the lever L, which is swung back until it 60 hangs close to the outside of the tank. The charging door clamp 35 is then swung back so that the charging door 27 may be removed. After carbide has been charged into the hopper, the door and clamp are replaced. 65 Sufficient water may now be introduced into

the generator through the open top of the float chamber. The feed pan A is also completely filled with water, and the generator is ready for the production of acetylene.

In starting the generator, it is desirable to hold down the feed lever with one's hand to permit the free discharge of carbide from the hopper until a sufficient supply of gas is generated. The pressure of the gas forces down the level of the water in the generating chamber and raises the level a corresponding amount in the buoyancy chamber. The rod 11 is hooked onto the lever L as soon as the water rises to buoy the feed pan enough to relieve the valve spring of some pressure so that it may raise the carbide feed valve into the outlet of the hopper to shut off the feed of carbide. As noted before, the acetylene gas passes from the generating chamber to the filter where it is cleaned. After leaving the filter, it passes through the regulator and back pressure valve to the service fitting. When the lines have been cleared of air and only acetylene is issuing from the generator, a rubber hose may be coupled to the service fitting to conduct the gas to a blowpipe or other apparatus for consumption. As the gas is consumed, the pressure falls in the generating chamber with a proportionate fall in the water level in the buoyancy chamber.

90 The feed pan descends with a fall in water level and opens the carbide feed valve, as already explained, admitting carbide into the generating chamber. The falling carbide is deflected away from the lower end of the partition so that it will not be carried into the buoyancy chamber by the movement of the water, and the deflector 54 that extends across the major portion of the bottom of the float chamber keeps the evolved gas from entering the latter. As the gas accumulates in the generating chamber the pressure rises therein, and forces the water level upwardly in the buoyancy chamber which causes the feed pan to close the feed valve as described heretofore. If for any reason the feed valve is not closed when the predetermined pressure is reached, so that gas continues to accumulate and to increase the pressure in the generating chamber, the water is driven below the leg 57 of an over-generation vent 58 through which the excess volume is released. The over-generation vent comes into play whenever there is a column of water in excess of 26 inches in the float chamber. A 26" column of water corresponds to less than one pound pressure so that excessive gas pressures cannot be built up in the generator. The surplus gas may be discharged through a suitable fitting attached to the upper part of said vent and projecting through the upper part of the partition into the buoyancy chamber.

100 In the event that excess pressure is applied to the feed lever or that a failure occurs in 105

the feed mechanism in the hopper, the shut-off valve which is just above the carbide feed valve closes the hopper opening so as to prevent the charge of carbide from falling 5 through, and interacting with the water to generate an excessive quantity of acetylene. By this arrangement the generator is safely 10 protected against improper operation of the device or accidental failure of the feed control mechanism. To safeguard the generator further and prevent its operation by unauthorized persons, suitable locking means may be provided therefor, such as a padlock which can be locked through the hole 25' 15 in the plunger 25 and so prevent the operation of the generator or the opening of the charging door. This padlock may be chained to the generator so that it will not become misplaced or lost.

20 The improved generator is automatically controlled by a simple but sensitive feed mechanism, and its construction is rugged, compact, and practically free from projecting parts, all of which especially adapt it for 25 portable service.

While a preferred construction is illustrated and described, it is to be understood that changes may be made in various parts without departing from the scope and spirit 30 of the invention.

I claim:

1. In an acetylene generator, the combination with a generating chamber and a buoyancy member chamber in hydraulic communication with each other, of mechanism for automatically feeding carbide to said generating chamber comprising a heavier-than-water buoyancy member operating in said buoyancy member chamber, and means for 40 partially supporting the weight of said buoyancy member.

2. In an acetylene generator, the combination of a generating chamber and a buoyancy member chamber in hydraulic communication with each other, whereby displacement of water in said generating chamber displaces water in said buoyancy member chamber; and mechanism for automatically feeding carbide to said generating chamber comprising a heavier-than-water buoyancy member adapted to contain water and means partially supporting the weight of the buoyancy member in said buoyancy member chamber so that the buoyancy of the water in the latter is adapted to cause said buoyancy member to be raised and lowered in accordance with changes of water level in said generating chamber.

3. In an acetylene generator, the combination of a tank adapted to contain water and having a partition terminating above its bottom to provide a generating chamber and a buoyancy chamber in hydraulic communication with each other, a carbide hopper in said 65 generating chamber, a valve therefor, a

heavier-than-water buoyancy member in said float chamber, an operative connection between the valve and said buoyancy member, and a resilient member partially supporting said buoyancy and tending to close said valve.

4. A device as claimed in claim 3 in which the operative connection between the valve and said buoyancy member comprises a lever extending transversely of said partition.

5. In an acetylene generator, the combination with a generating chamber and a buoyancy chamber in hydraulic communication with each other, of a carbide hopper contained within the generating chamber, a carbide feed valve, means positioned within the said hopper to support said valve and tending to hold said valve in a closed position, and a heavier than water buoyancy member operative to open said feed valve when the water in the buoyancy chamber falls below a predetermined level.

6. In an acetylene generator, the combination with a generating chamber and a buoyancy chamber in hydraulic communication with each other; of a carbide hopper contained within said generating chamber; a conical carbide feed valve adapted to project into the feed mouth of said hopper from the exterior thereof; means positioned within the said hopper to support the said valve; resilient means associated with aforesaid means tending to hold said valve in a closed position; and means comprising a heavier than water buoyancy member in said buoyancy chamber, operative to depress said conical valve to permit a discharge of carbide from said hopper.

7. In an acetylene generator, the combination with a generating chamber and a buoyancy chamber in hydraulic communication with each other, of a carbide hopper secured to the top of said generating chamber, a charging door for said hopper, a diaphragm joined by a gas-tight connection to the underside of said door, an actuating plunger carried by said diaphragm and extending above said charging door, a feed valve for said hopper, a valve rod supporting said feed valve, said rod being depressible by said plunger, a spring tending to hold said valve normally in a closed position, a feed pan containing water movable in accordance with the water level in the buoyancy chamber, and means whereby feed pan operates said plunger to control the opening of the carbide feed valve.

In testimony whereof, I affix my signature.
JOHN L. MANDEVILLE.
